MEAT TENDERIZING MACHINE

Henry Lowell Byland, Deerfield, Ill., assignor to U. S.
Slicing Machine Company, Inc., La Porte, Ind., a cor-
poration of Indiana

Application May 29, 1957, Serial No. 46,406

Term of patent 14 years

(Cl. D11—1)

FIG. 1

FIG. 2

Fig. 1 is a perspective view showing the front and right-hand end of the meat tenderizing machine embodying the new design; and

Fig. 2 is a perspective view showing the rear and left-hand end of the meat tenderizing machine.

The dominant features of the design reside in the portion shown in full lines.

This application is a continuation-in-part of my co-pending application Serial No. D.43,278, filed October 9, 1956.

I claim:

The ornamental design for a meat tenderizing machine, as shown and described.
